BAILER

August A. Melo, Taft, Calif., assignor to
Paul Cavins, Los Angeles, Calif.

Application October 4, 1932, Serial No. 636,219

3 Claims. (Cl. 166—19)

1. This invention relates to bailers and has relation more particularly to a device of this kind especially designed for use in connection with oil or other deep wells, and the invention has for its 5 object to provide a brazier constructed in a manner to allow the ready passage therethrough of any fluid which may be standing in the bottom of the well as the brazier is lowered to remove sand or other material which may have accumulated 10 in the hole.

Another object of the invention is to provide a device of this kind comprising an elongated barrel 15 which is mounted a tubular swab together with means operating from the top of the well for moving the swab in a direction to draw the solid material within the barrel and also operating as a means to lift the brazier out of the hole.

A further object of the invention is to provide a device of this kind wherein sand or other loose 20 solid material is drawn into the barrel of the brazier as a result of a vacuum created within the barrel and wherein such material is effectively retained within the barrel until after the brazier has been withdrawn from the hole.

It is also an object of the invention to provide 25 a device of this kind constructed and assembled in a manner whereby the brazier may be readily prevented from being held by such suction to the bottom of the hole and wherein the brazier in its 30 construction provides an effective jarring means to release the brazier in the event it becomes stuck in the hole.

The invention consists in the details of construction and in the combination and arrangement 35 of the several parts of my improved brazier whereby certain important advantages are attained and the device rendered simpler, less expensive and otherwise more convenient and advantageous for use, as will be hereinafter more 40 fully set forth.

The novel features of my invention will hereinafter be definitely claimed.

In order that my invention may be the better understood, I will now proceed to describe the 45 same with reference to the accompanying drawing, wherein:—

Figure 1 is a view partly in section and partly in elevation of a brazier constructed in accordance with an embodiment of my invention;

Figure 2 is a view similar to Figure 1 showing certain of the parts in a second position;

Figure 3 is an enlarged fragmentary view partly in section and partly in elevation illustrating in detail certain of the features of the brazier as 55 herein disclosed;

Figure 4 is a sectional view taken substantially on the line 4—4 of Figure 3;

Figure 5 is a view in bottom plan of the brazier as illustrated in Figure 3;

Figure 6 is a view in elevation of the outer 5 end of one of the holding screws herein employed.

As disclosed in the accompanying drawing, 10 I denotes a barrel of desired dimensions having the upper portion of its wall provided therethrough with the vents 2 and which is also provided with an internal annular shoulder 3 against which abuts a ring 4 snugly engaging within said lower end portion of the barrel 1. This ring 4 in its periphery is provided with a surrounding groove 5 and engaging within said groove 5 are the holding screws 6 preferably three in number and threaded through the wall of the barrel 1. The outer end portion of each of these screws 6 is provided with a socket 7 angular in cross section and in which is adapted to be engaged a 15 suitable key to facilitate the desired adjustments of the screw to engage the same with the applied ring 4 or to free the same from said ring so that the ring can be removed.

The central opening 8 defined by the ring 4 has 20 retrograde flow therethrough prevented by a non-return valve 9 herein disclosed as a flap valve coacting with the inner face of the ring 4 and opening inwardly of the barrel 1. This flap valve 9 is hingedly connected, as at 10, to the ring 4. 25

Mounted within the bore of the barrel 1 for movement lengthwise thereof is an elongated tubular swab 11 having disposed around and held thereto the packing cups 12 for effective coaction 30 with the wall of the bore of the barrel 1. The lower end portion of this swab 11 is formed to provide a valve seat 14 with which coacts a valve member 15. This valve member 15 is carried by an end portion of a rod 16. This rod 16 is directed 35 axially through the swab 11 and has its upper end portion coupled, as at 17, to a butterfly 18.

This butterfly 18 in turn is connected, as at 19, to the lower end portion of a rod or kindred rigid member 20 which extends to the top of the 40 well. The upper end of the butterfly 18 provides a shoulder 21 surrounding the rod 20 and which is adapted to have contact with the inserted end of a conventional head 22 threaded or otherwise engaged within the upper portion of the barrel 45 1, said applied head 22 serving as an anvil as will be hereinafter referred to.

The rod 20 above the applied head 22 is surrounded by a spring 23 of requisite tension and which serves as a bumper for engagement with 50 55

the head 24 carried by the extended portion of the rod 20.

The bailer, as herein disclosed, is primarily intended to be used to remove from the bottom of an oil or water well material, such as sand, which has accumulated in the hole and which accumulated material prevents efficient entry into and removal from the well of the fluid sought to be produced. As the bailer is lowered into the hole, the valve 9 is forced open by the pressure or/and resistance of the fluid standing in the hole. At this time the valve 15 is in open position as illustrated in Figure 2 and the fluid standing in the hole passes up through the barrel 1 15 and the swab 11 out through the vents 2. As the bailer penetrates the accumulated material within the bottom of the hole as desired, upon withdrawal or lifting movement on the rod 20 the valve 15 immediately engages its seat 14 at the lower end of the swab 11 and said valve 15 is maintained seated throughout the entire withdrawing or pulling operation. As the valve member 15 effects the upward movement of the swab 11 a vacuum is formed below the valve member 15 drawing within the barrel 1 from the bottom of the hole or well the solid material sought to be removed, such as sand or shale.

When the shoulder 21 at the top of the butterfly 18 reaches or contacts with the inserted or inner end of the head or anvil 22, the movement is stopped of the swab 11 independently of the barrel 1 and at which time the barrel 1 below the swab 11 and its closed valve 15 is filled with the material for removal. The entire bailer is then hoisted to the top of the well for dumping.

It is to be particularly noted that in the invention as herein disclosed the valve 15 cannot fail to close due to the fact that said valve is subjected directly to the pull from the top of the hole or well through the rod 20. It is also believed to be apparent that when the bailer is being lifted the valve 9 will close and be maintained closed by the weight of the contained material within the barrel 1.

When the bailer has been withdrawn from the well or hole the screws 6 are retracted to allow the ready removal of the ring 4 and the valve 9 carried thereby whereupon the material contained within the barrel 1 may be readily dumped therefrom.

It sometimes happens that the entire bailer becomes stuck in the bottom of the hole. By a quick jerk on the bailer the shoulder 21 of the butterfly 18 will be caused to butt against the inner or inserted end of the head or anvil 22 thus dislodging the entire bailer. A quick jerk will also compel the required engagement of the valve member 15 with its seat 14 and thus prevent sanding up of the bailer on the inside.

The operating rod 20, the hammer 21, and the valve 15 are capable of limited independent movement with respect to the swab 11, by reason of the fact that the distance between the valve 15 and the butterfly 18 is greater by a substantial amount than the length of the swab 11. If the barrel is stuck in the mud at the bottom of the well when the swab is drawn to its uppermost position as in Figure 1, the hammer 21 may be lowered and raised sharply between the anvil 22 and the top of the swab 11 to strike the anvil and jar the barrel to dislodge the same from the mud. By reason of this lost motion connection, the barrel may be jarred without moving the swab upwardly to create additional suction in the barrel, and thus there will be no tendency for the

barrel to become more deeply embedded as a result of the jarring action.

Upon forcing the rod 20 downwardly at any time the valve member 15 will be moved into open position and this is of advantage when for any reason it is desired to break the vacuum or partial vacuum being formed in the barrel 1 below the swab 11. This is particularly desirable in the event there is such suction action in the material at the bottom of the well or hole which the bailer has penetrated to have a tendency to bind or hold the bailer as an entirety to the bottom of the hole or well in such a way as to interfere with the withdrawal or lifting of the bailer.

As is particularly illustrated in the accompanying drawing, it is to be noted that the inner marginal portions of the packing cups 12 are engaged between the members 25 and 25' snugly surrounding the swab 11, the lowermost member 25' being threaded on the swab and serving as a means to maintain the inner marginal portions of the cups 12 in desired assembly. Outwardly of the member 25' the swab 11 has threaded thereon a holding or locking member 26 which coacts with the member 25'. The outer end of this member 26 as is clearly illustrated in Figure 3 is of increased thickness and the outer surface substantially flush with the adjacent lower end of the swab 11 and is comprised in the seat 14 for the valve member 15. It is believed to be apparent that in addition to serving as a holding or retaining medium, the member 26 can be readily replaced when it is desired to renew the seat at the lower end of the swab 11 for the valve member 15.

It will be noted that the top edge of the uppermost packing cup 12 is adapted to engage the outwardly directed surface 27 on the exterior of the swab. By screwing the lowermost member 25' upwardly on the swab to compress the packing, the top end of the uppermost packing cup 12 will be pressed outwardly along the surface 27 of the swab, thus serving to expand the packing at this point to insure that the swab is held firmly against the inner surface of the barrel.

If the swab has the tendency to slide up and down in the barrel, the compression of the packing may be adjusted by the lowermost threaded ring 25' in order to hold the swab stationary against the inner surface of the barrel except when it is positively moved by the valve member 15 or the butterfly 18.

If the lower end of the barrel becomes stuck in the mud as discussed above, and when the swab is moved by the valve member 15 to its uppermost position, the compressed packing will hold the swab against vertical movement with respect to the barrel while the rod 20 is being lowered and raised sharply to impact the hammer 21 against the anvil 22 to dislodge the barrel from the mud.

From the foregoing description it is thought to be obvious that a bailer constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A device of the character described com-

prising a barrel having a bottom inlet, an anvil connected to said barrel, a swab frictionally mounted in and adapted for longitudinal movement in said barrel to draw material through the bottom inlet, means extending from within the barrel to the exterior thereof for moving said swab in said barrel, said means being capable of limited independent movement with respect to said swab, and a hammer carried by said means and by reason of said independent movement adapted to impact said anvil to dislodge the barrel when stuck in the well without moving said swab with respect to said barrel while the hammer is being impacted.

15 2. A device of the character described comprising a barrel having a bottom inlet, a swab frictionally mounted in and adapted for longitudinal movement in said barrel to draw material through the bottom inlet, a top for said barrel to limit the upward movement of said swab, and means extending from within the barrel to the exterior thereof for moving said swab in said barrel, said means being capable of limited independent movement with respect to said swab

without moving said swab with respect to said barrel.

3. A device of the character described comprising a barrel having a bottom inlet, an anvil connected to said barrel, a swab frictionally mounted in and adapted for longitudinal movement in said barrel to draw material through the bottom inlet, said swab having a fluid passage therethrough, operating means extending through the swab passage for moving said swab in said barrel and having limited movement independent of said swab, a member carried at the lower end of said operating means to open the swab passage on movement of said means in one direction and to close the swab passage on movement in the opposite direction, said member acting upon further movement of said operating means in said opposite direction to move said swab in the barrel, and a hammer carried by said operating means and by reason of said independent movement adapted to impact said anvil to dislodge the barrel when stuck in the well, without moving and means to hold said swab with respect to said barrel while the hammer is being impacted.

CERTIFICATE OF CORRECTION.

Patent No. 2,041,720.

May 26, 1936.

AUGUST A. MELO.

It is hereby certified that error appears in the printed specification of the above numbered patent requiring correction as follows: Page 3, second column, lines 22 and 23, claim 3, strike out the words "and means to hold"; and that the said Letters Patent should be read with this correction therein that the same may conform to the record of the case in the Patent Office.

Signed and sealed this 27th day of April, A. D. 1937.

Leslie Frazer
Acting Commissioner of Patents.
